UNITED STATES PATENT OFFICE.

HIRAM H. HERST, OF OCEAN VIEW, VIRGINIA.

SHIRT.

1,342,906.

Specification of Letters Patent.

Patented June 8, 1920.

Application filed April 8, 1919. Serial No. 288,499.

To all whom it may concern:

Be it known that I, HIRAM H. HERST, a citizen of the United States, and a resident of Ocean View, in the county of Norfolk and State of Virginia, have made certain new and useful Improvements in Shirts, of which the following is a specification.

My present invention relates generally to men's wear, and more particularly to men's outer shirts, my object being the provision of a novel construction in connection with the front portion of a shirt to conceal and hold the flowing ends of fore-in-hand ties and thus adapted particularly to summer wear without a vest.

A further object of the invention is to provide a construction which will enable a better fit in the front of a shirt, and while especially designed for summer wear, will also promote certain advantages in winter wear, in connection with vests as I will hereinafter more particularly point out.

In carrying out my invention I provide a shirt, the upper inner portions of the front sides of which are cut away and are formed as to provide a V-shaped outlet, and my present improvements are directed in particular to the manner in which the edges of the front sides or fore part of the shirt are formed along the sides of the outlet so as to retain their shape in laundering and without detracting from their appearance and wear and without extra stitching and securing of parts.

In the accompanying drawings illustrating my invention, and forming a part of this specification,

Figure 1 is a perspective view illustrating the practical application of my invention,

Fig. 2 is a perspective view looking at the front of a shirt, partly open and constructed in accordance with my improvements,

Fig. 3 is a detail perspective view of one of the fore flaps underlying the outlet of the shirt front,

Fig. 4 is a perspective view of one of the front sides of the shirt removed, with its border flap extended,

Fig. 5 is a similar view showing the border flap folded in place,

Fig. 6 is a perspective view of one side portion of a garment constructed in accordance with my invention, and

Fig. 7 is a cross section through a por-

tion of one of the front sides and its underlying flap.

Referring now to these figures, it will be noted particularly from Figs. 1, 2, and 6 that my invention proposes the formation of each of the front sides 10 of a shirt in such manner that a V-shaped outlet results at the upper front portion of the shirt, in connection with front flaps 11 attached around their upper curved edges as at 12 to the collar band 13 and at their upper straight edges 14 as seen in Fig. 3 to the shoulder seam seen at 15 in Fig. 6 in particular.

The free inner straight edges 16 of the front flaps 11, which latter are of course of a greater combined area than the area of the outlet on the shirt front, are lapped and fastened according to the usual way of fastening the front portion of a shirt, as for instance, by a button 17 and a button hole 18, and the lower portions or straight edges of the fore sides or front sides 10 of the shirt are likewise fastened as usual by buttons 19 and button holes 20.

The upper button hole 20, it will be noted by particular reference to Figs. 4 and 5, is located immediately adjacent to the lower end of the upper angular portion of the respective front side, as well as the upper button 19, and these upper angular portions 21 of the two fore sides which coöperate to form the V-shaped front outlet, have border flaps 22, one of which is particularly seen in Fig. 4 and the upper and lower ends of which border flaps are flared on angles at 23 and 24' so that the border flaps when folded will have their upper ends 23 coincide with the upper straight edges 24 of the front sides, and their lower ends 24' will be perforated when the upper button hole 20 is formed and will be secured when the button hole is worked as usual.

In view of the fact that when the flaps 22 are folded against the inner faces of the front sides of panels 10, the upper ends 23 of these panels coincide with the upper straight edges 24 of the panels, it is obvious that the upper ends of the flaps in their turned positions will be secured by the shoulder seam 15 as seen in Fig. 6, so that without other connection, the border flaps along the upper angular portions 21 of the front panels will be held against displacement and

will form a turned edge which is permanently supported, and is of a nature adapted to prevent a neat appearance in use and avoid all tendency to displacement in laundrying.

It is obvious that when the shirt is buttoned down the front, the flowing ends of a tie may be concealed beneath the same by virtue of the extension of the tie downwardly between underlying flaps 11, through the upper V-shaped outlet, and that my invention not only provides for this outlet and the edges incident thereto, but also avoids all danger of the edges thereof being forced out of place during laundrying without however requiring extra stitching or securing means in view of the fact that the two border flaps are held at their upper edges by the shoulder seams and that their lower edges by the upper buttons 19 and button holes 20.

It is also obvious that a vest-like appearance will be given, which is both neat and attractive, and that while particularly de-

signed for summer wear, the shirt formed in accordance with my invention has advantages in winter wear by virtue of the angular edges 21 forming what are known as "vest edging."

I claim:—

A shirt for men's wear having plain rear panels and front panels connected by shoulder seams, its front panels being cut away angularly along the upper, inner and adjacent edges to form V-shaped outlets at the upper central portion of the shirt front, each of said front panels being provided with integral flaps turned bordering the said upper angular portions and turned beneath the inner edges of the said front panels, the upper ends of which border flaps are secured in the shoulder seams, and fastening means for connecting the front panels in use, the upper members of which secure the lower ends of the said border flaps in place whereby the flaps will be securely held at the ends only.

HIRAM H. HERST.
